CONTROL FOR FUEL SUPPLIES

Stanley M. Udale, Detroit, Mich., assignor to
George M. Holley and Earl Holley

Application August 23, 1940, Serial No. 353,782

3 Claims. (Cl. 261—69)

The object of this invention is to control the rate of fuel flow to either a carburetor or to a fuel injection system by means of the air flow through a venturi and the flow of the fuel through a fuel venturi.

In the drawing, the figure shows diagrammatically the application of the device to a carburetor.

In the figure, 10 is the air entrance controlled by two valves 11 and 12 connected by linkage 13, which valves in the position shown permit warm air to enter the air entrance 10. Associated with the air venturi 14 is an annular chamber 15 communicating through the opening 16 with the throat of the venturi 14. 17 is the corresponding fuel venturi which derives its fuel from the fuel pipe 18, the fuel flowing to the chamber 19 and down past the needle 20 through a passage 21 to the fuel outlet 22, which fuel outlet is controlled by a needle 23, which needle is controlled by a bell crank lever 24 mounted on the pin 25. The needle 23 is connected through this bell crank lever with the rod 26 and is kept in engagement by means of the compressed spring 27 which is adjusted by the threaded screw 28. The rod 26 carries an enlargement 102 located in the throat of the venturi 17. The diaphragm 28 is responsive to the fuel pressure in the chamber 19. The chamber 29 above the diaphragm 28 is therefore at the pressure existing in the throat of the fuel venturi 17, for the reason that the passage 30 connects the throat of the venturi 17 with the chamber 29. A rod 31 connects the diaphragm 28 and the rod 26 with another diaphragm 32 which forms the upper wall of a chamber 33.

The pin 31 slides through an opening in the wall 34 which forms the partition between the chamber 29 and the chamber 33. A small quantity of fuel therefore leaks past the pin 31 into the chamber 33 and so finds its way to the annular chamber 15 and so to the passage 35, where it discharges through the openings 36 and 37. A chamber 39 is located above the diaphragm 32 and is connected through a passage 40 with the annular chamber 9 and so with the openings 41 in the outlet from the venturi 14. An aneroid barometer 42 operates through a lever 43 with a valve 44 which at high altitude permits a flow of air from the chamber 39 to the chamber 33. This is the well known altitude correction to correct for the changes of density in the air.

In order that the delay inevitable between the opening of the throttle 38 and the opening of the needle valve 23 does not disturb the mixture

ratio, a pipe 98 is provided. This pipe connects the mixture outlet with a chamber 92 bounded on its right by a diaphragm 93 supported by a spring 94. When the throttle is closed, a diaphragm 93 is drawn by suction to the left. When the throttle is opened the diaphragm moves under the influence of the compressed spring 94 to the right, compressing the air in the chamber 93. A pipe 96 transmits this pressure to the chamber 39 where the pressure is slightly increased and a temporarily rich mixture is produced to take care of the delay above referred to.

Operation

Assuming that the engine connected to this particular carburetor is already running, then the throttle 38 causes a suction at the outlet 37 located near the downstream lip of the throttle so as to cause air flow from the opening 36, causing the idle fuel to be drawn down the passage 35 from the annular chamber 15 and so from the chamber 33. This causes a slight suction in the chamber 33 which increases as the throttle opens. Later, when the throttle opens beyond the range of 36, 37, the suction in the throat of the venturi 17 increases still more and the diaphragm 32 descends compressing the spring 26 and opening the needle 23, thereby causing an increase in the fuel flow through the venturi 17, which causes the diaphragm 28 to rise because of the suction in the chamber 29. A balance is thus reached in which the mixture ratio is determined by the relative area of the throats of the venturis 17 and 14 and therefore by the diameter of the rod 26 at the throat and the enlargement 102 is located here.

It is desirable at extremely low fuel flows and at extremely high fuel flows that the mixture ratio should be rich, richer by say 50%, than the cruising lean mixture ratio. To attain this result the rod 26 has a definite contour as indicated by the enlargement 102. When the throat of the venturi 17 is small a relatively small fuel flow will cause a great suction in the chamber 29 and therefore will balance a relatively great air flow through the venturi 14. In other words, a lean mixture will result. When the throat of the fuel venturi 17 is large a relatively large flow through the venturi 17 is required to balance a relatively smaller flow through the venturi 14. In other words, a rich mixture results. Although it is not absolutely necessary a bumper spring 44 is provided above the diaphragm 32. The en-

largement 102 in the rod 20 thus controls the mixture ratio at various engine loads.

What I claim is:

1. A fuel supply system for an internal combustion engine comprising an air entrance, a venturi in the air entrance, an outlet from the venturi, a throttle valve in said outlet, a fuel entrance a streamlined obstruction located in the throat of said fuel venturi, a venturi in said entrance, an outlet from said fuel venturi, a valve located some distance away from said venturi in said outlet from said fuel venturi, a diaphragm responsive to the pressure difference created by the fuel venturi, a second diaphragm responsive to the pressure difference created by the air venturi, manual means for controlling the air throttle, means for rigidly connecting the two diaphragms together, said diaphragms being adapted to be in equilibrium when subjected to the fuel and air pressures corresponding to the normal fuel and air flows, said connecting means being also connected to the fuel throttle valve and to the streamlined obstruction located in the throat of the said fuel venturi so as to form therewith an automatically variable throat and in which the maximum diameter of the obstruction is located at the minimum diameter of the venturi at a fuel flow intermediate the maximum and minimum fuel flows.

2. A fuel supply system for an internal combustion engine comprising an air passage, a venturi therein, an air valve regulating the air flow, a fuel entrance, a fuel passage conducting fuel to said engine, a fuel venturi therein, a streamlined obstruction located in the throat of said fuel venturi; an outlet orifice located in said fuel passage adapted to discharge fuel into said air passage, a fuel throttle valve regulating the size of said orifice, a diaphragm responsive on one side to the fuel pressure and on the other side to the pressure in the throat of said fuel venturi.

5 a second diaphragm responsive on one side to the suction in the throat of the air venturi, and on the other side to the normal pressure in the air passage, means for rigidly connecting the two diaphragms together, said diaphragms being adapted to be in equilibrium when subjected to the fuel and air pressures corresponding to the normal fuel and air flows, said connecting means being also connected to the fuel throttle valve and to the streamlined obstruction located in the throat of the said fuel venturi so as to form therewith an automatically variable throat and in which the maximum diameter of the obstruction is located at the minimum diameter of the venturi at a fuel flow intermediate the maximum and minimum fuel flows.

10 3. A fuel supply system for an internal combustion engine comprising an air passage, a venturi therein, an air valve regulating the flow through said venturi, said valve constituting the only movable obstruction in the air passage, a fuel entrance, a fuel venturi therein, an outlet from said venturi, a streamlined obstruction located in the throat of said venturi, a fuel throttle valve located some distance away from said venturi in said outlet from said venturi, a diaphragm responsive to the pressure drop in the throat of the fuel venturi, a second diaphragm responsive to the drop in the throat of the air venturi, means for rigidly connecting the two diaphragms together, said diaphragms being adapted to be in equilibrium when subjected to the fuel and air pressures corresponding to the normal fuel and air flows, said connecting means being also connected to the fuel throttle valve and to the streamlined obstruction located in the throat of said fuel venturi for moving said obstruction relative to said venturi for the purpose of varying the effective throat diameter of said fuel venturi.
